UNITED STATES PATENT OFFICE.

ANDREW EPPLER, OF LYNN, MASSACHUSETTS, ASSIGNOR TO UNITED SHOE MANUFACTURING CORPORATION, OF PATERSON, NEW JERSEY, A CORPORATION OF NEW JERSEY.

INSEAM-SEWING MACHINE.

Application filed August 18, 1919, Serial No. 318,086. Renewed November 21, 1923.

To all whom it may concern:

Be it known that I, ANDREW EPPLER, a citizen of the United States, residing at Lynn, in the county of Essex and State of Massachusetts, have invented certain new and useful Improvements in Inseam-Sewing Machines; and I do hereby declare the following to be a full, clear, and exact description of the invention, such as will enable others skilled in the art to which it appertains to make and use the same.

The invention relates to inseam sewing machines such as are used to sew the upper to the sole of a turn shoe or to sew the welt and upper to the insole of a welt shoe.

The primary object of the invention is to so construct and operate the feeding devices that the shoe may be more easily and uniformly swung and manipulated and the stitches be more uniformly distributed and tightened in sewing about pointed toes than is practicable with the constructions heretofore in common use. To this end a multiple step (preferably a two-step) feed is given to the shoe during each stitch-forming cycle. With this form of feed the spread between the needle and the channel guide while the needle is in the work need be but approximately one-half the spread required by the usual single step feed, and consequently the shoe may be swung and manipulated to better advantage and a better distribution of the stitches and a tighter seam be secured in sewing about pointed toes, as will be apparent to those familiar with the conditions obtaining in sewing about such toes.

The invention is shown in the accompanying drawings in which Fig. 1 is a front elevation showing so much of an inseam sewing machine as is necessary to illustrate the application of the preferred form of the invention thereto; Fig. 2 is a side elevation of the same and Figs. 3-8 are diagrammatic views indicating the mode of operation of the awl and channel guide in feeding the work.

In the drawings the invention is shown embodied in a welt and turn sewing machine having the general construction of the machine shown and described in Patent No. 1,108,560, August 25, 1914. The machine is provided with a curved hook needle 2, a looper 4, a thread arm 6, an awl 8, a channel guide 10, a back gage 12 (which in sewing

welt shoes is in the form of a welt guide) and a back rest 14, all of which are similar in construction to the corresponding parts in the machine of the patent referred to and all of which with the exception of the awl and channel guide are operated in the same manner.

In modifying the machine of the above patent to embody the present invention, the awl and channel guide are so mounted and operated that they give two feeding movements to the work between successive work piercing strokes of the needle, each of which is one-half the length of the stitch being sewed. The maximum spread between the needle and channel guide is therefore but approximately one-half the spread required for the same length of stitch with the prior single step feed, thus permitting better distribution of the stitches and the sewing of a tighter seam about pointed toes. In the construction shown the awl carrier segment 15 is mounted upon a feed slide 16, similar to the feed slide of the patent above referred to and mounted to slide in a similar manner upon fixed studs 18 and 20. The awl segment is oscillated as in the machine of the above patent through a lever 22 mounted on the slide and connected by a link 24 with the awl segment and by a pivot pin 26 with the cam operated lever 28. The slide 16 is reciprocated in the line of feed by a feed cam groove formed in the cam disk 30 and engaging a roll 32 carried by the slide. The channel guide is secured upon a carrier lever 34 which is mounted to rock and to slide in the direction of the feed upon a stud 36 secured in the feed slide 16. The lever 34 is rocked to move the channel guide in and out by an arm 38 secured to a rock shaft 40 and provided at its lower end with a tooth engaging a tooth space on the end of the lever 34. The rock shaft 40 is operated through a cam lever 42 secured to the shaft and provided at its rear end with a roll 44 engaging a cam groove 46 in the disk 30. The lever 34 is reciprocated in the line of feed by a cam lever 46 the forward end of which is provided with a tooth space engaged by a tooth on the hub 105 of lever 34, and the rear end of which is provided with a roll 48 engaging a cam groove in the disk 30.

The mode of operation in giving the work a multiple step feed during each stitch-

forming cycle is indicated diagrammatically in Figs. 3-8. Assuming that the needle has withdrawn from the work during its back stroke, the awl and channel guide will 5 be in engagement with the work a half-stitch length from the last needle hole, as indicated in Fig. 3. As the needle completes its backward stroke the channel guide and awl move forward in the direction of 10 feed and advance the work a half-stitch length, as indicated in Fig. 4. The awl then remains in engagement with the work while the channel guide is moved out and retracted or back fed and again moved in to engage 15 with the work, as indicated in Fig. 5. The awl is then moved out to disengage the work and retracted or back fed and then engaged with the work, as indicated in Fig. 6. The awl and channel guide then again 20 advance in the direction of feed to advance the work a second half-stitch length, as indicated in Fig. 7. During this feed of the work the needle advances and as it enters the work the awl is retracted, the 25 channel guide staying in while the needle completes its forward stroke and while the looper is acting. The channel guide is then moved out and the awl and channel guide back feed and the channel guide goes in, 30 as indicated in Fig. 8. As the needle is retracted the awl is moved forward into engagement with the work, as indicated in Fig. 3, thus completing the cycle. The channel guide and awl thus gives the work 35 two feeding steps of a half-stitch length each during each stitch-forming cycle with the resulting advantages above set forth.

While it is preferred to employ the specific construction and arrangement of parts 40 shown and described in embodying the invention in the machine of the patent referred to, it will be understood that this construction and arrangement is not essential to the broader features of the invention 45 and that it may be varied or modified as found desirable or best suited to the construction and mode of operation of the machine in which it is to be embodied.

What is claimed is:

- 50 1. An inseam sewing machine having, in combination, stitch-forming mechanism, devices for guiding and intermittently feeding the shoe, and mechanism for actuating the feeding devices to give a multiple step feed to the shoe in each stitch-forming cycle.
- 55 2. An inseam sewing machine having, in combination, stitch-forming mechanism, devices for guiding and intermittently feeding the shoe, and mechanism for actuating the feeding devices to give a two-step feed to the shoe in each stitch-forming cycle.

3. An inseam sewing machine having, in combination, a needle, a channel guide, an awl, and mechanism for actuating the awl and channel guide to give the shoe a multiple step feed in each stitch-forming cycle. 65

4. An inseam sewing machine having, in combination, stitch-forming mechanism, a channel guide, an awl, and mechanism for giving the awl and channel guide two half-stitch length feeding movements in each 70 stitch-forming cycle.

5. An inseam sewing machine having, in combination, a needle, a channel guide, an awl arranged to engage the channel, mechanism for moving the awl and channel guide together in the direction of the feed and for independently back-feeding them. 75

6. An inseam sewing machine having, in combination, a needle, a channel guide, an awl, mechanism for giving the awl and channel guide two feeding movements between successive work piercing strokes of the needle and for back-feeding them successively after the first of the said feeding 85 movements. 80

7. An inseam sewing machine having, in combination, a needle, a channel guide, an awl, mechanism for giving the awl and channel guide two feeding movements between successive work piercing strokes of the needle and for back-feeding them after the second feeding movement while the needle is in the work and for back-feeding them successively between the two feeding 95 movements. 90

8. An inseam sewing machine having, in combination, stitch-forming mechanism, a channel guide, and mechanism for giving the channel guide two forward and return 100 movements in the line of feed in each stitch-forming cycle. 100

9. An inseam sewing machine having, in combination, stitch-forming mechanism, an awl arranged to engage the channel and mounted for movement in the line of feed, and a channel guide mounted for independent movement in the line of feed. 105

10. An inseam sewing machine having, in combination, a needle, a channel guide, an awl in advance of the channel guide, mechanism for advancing the awl and channel guide together in the direction of the feed and for returning them independently. 110

11. An inseam sewing machine having, in combination, a needle, a channel guide, mechanisms for actuating the needle and channel guide timed to back feed the channel guide less than a stitch length while the needle is in the work. 115
